UNITED STATES PATENT OFFICE.

GEORGE T. SOUTHGATE, OF BROOKLYN, NEW YORK.

HIG. POTENTIAL SWITCH.

1,310,585.

Specification of Letters Patent. Patented July 22, 1919.

Application filed October 6, 1917. Serial No. 195,027.

To all whom it may concern:

Be it known that I, GEORGE T. SOUTHGATE, a citizen of the United States, residing at Brooklyn, in the county of Kings and State of New York, have invented certain new and useful Improvements in High-Potential Switches; and I do hereby declare the following to be a full, clear, and exact description of the invention, such as will enable others skilled in the art to which it appertains to make and use the same.

My invention relates to high potential switches.

One object of my invention is to provide a simple, cheap and efficient switch for the opening and closing of circuits carrying currents of electricity at high potentials.

A further object of my invention is to provide a switch having a minimum number of insulating parts.

A further object of my invention is to provide a switch having discharge horns so correlated with the contacting elements of said switch that when the circuit is opened the arc will be transferred from said contacting elements to said horns.

A further object of my invention is to provide a switch having a pair of contacts which move in opposite directions in order to increase the relative speed with which said contacts separate without increasing the absolute speed of said contacts.

These and further objects of my invention will be explained in the following specification, reference being had to the accompanying drawings, in which:

Figure 1 is a front elevation of my improved switch.

Fig. 2 is a view of the parts shown in Fig. 1 looking in the direction of the arrow 2. In Figs. 1 and 2 the sleet hoods around the contacts are omitted for the sake of clearness.

Fig. 3 is an enlarged detail view of one of the contacts viewed in the direction of the arrow 3 in Fig. 2.

Fig. 4 is a section along the line 4—4 of Fig. 3 looking in the direction of the arrows.

Fig. 5 is a view of the parts shown in Fig. 1 looking in the direction of the arrow 5.

Fig. 6 is a section along the line 6—6 of Fig. 4 looking in the direction of the arrows.

Fig. 7 is a diagrammatic plan view of the switch arms and contact blocks. 55

Figs. 8 and 9 are details of parts herein-after referred to.

In the drawings:

15 represents a base which is composed of the steel angles 16—16 which may be supported in any approved manner and which may be of any length so that any number of my improved switches may be mounted thereupon. 60

At each position where one of my improved switches is to be mounted a steel channel is secured to the underside of the horizontal legs of the angles 16—16 by means of rivets such as 18. 65

The gear housing 19 is secured to the angles 16—16 in any approved manner as by means of the bolts 20—20. 70

The gear housing 19 may be of any suitable shape and size but it is preferably formed with a bottom rib 21 and a top rib 75 22 near the center of each of which there are provided cylindrical holes 23 and 24 in which is revolubly mounted the operating shaft 25. The bevel gear 26 and the boss 27 formed integrally therewith are provided with a central cylindrical hole in which the shaft 25 fits tightly and said gear is secured to said shaft by means of the pin 28 which fits tightly in holes provided in the boss 27 and shaft 25. The upper flat sur-

face of the boss 27 is just below the lower flat surface of the top rib 22 and prevents upward motion of the shaft 25. Downward motion of the shaft 25 is prevented by the collar 29 which is secured to the shaft 25 by 80 the pin 30, the lower face of the collar 29 resting upon the upper surface of the bearing boss 31. The shaft 25 extends some distance below the bottom of the bottom rib 21 and the lever 32 fits tightly upon said 85 shaft and is secured thereto by means of the pin 33. The lever 32 is provided with the arms 34—34 in which is secured the pin 35 upon which and between the arms 34—34 there is mounted the clip 36, the latter being 90 secured in any approved manner to the operating rod 37.

The bearing boss 31 is provided with a cylindrical hole 38 and there is formed integrally with the top rib 22 the cylindrical 105 boss 45 provided with a cylindrical hole 39

axially in line with the hole 38. The bearing boss 31 is also provided with a cylindrical hole 40 and there is formed integrally with the top rib 22 the cylindrical boss 46 5 provided with a cylindrical hole 41 axially in line with the hole 40.

A switch shaft 42 is revolvably mounted in the holes 38 and 39 and the bevel gear 43 is provided with a central cylindrical hole 10 in which said shaft fits tightly and said gear is secured to said shaft by means of the pin 44. The upper face of the gear bearing against the inside face of the boss 45 serves to prevent upward displacement of the shaft 15 42 and the lower face of the collar 47 serves to prevent downward displacement of said shaft. The collar 47 is provided with a central cylindrical hole in which fits tightly the upper end of the shaft 42 and said collar is 20 secured to said shaft by means of the pin 48. The collar 47 is formed integrally with the flange 49.

A second switch shaft 50 is revolvably mounted in the holes 40 and 41 and the bevel gear 51 is provided with a central cylindrical hole 25 in which said shaft fits tightly and said gear is secured to said shaft by means of the pin 52. The upper face of the gear bearing against the inside face of the boss 46 30 serves to prevent upward displacement of the shaft 50 and the lower face of the collar 53 serves to prevent downward displacement of said shaft. The collar 53 is provided with a central cylindrical hole in 35 which fits tightly the upper end of the shaft 50 and said collar is secured to said shaft by means of the pin 54. The collar 53 is formed integrally with the flange 55.

The axes of the shafts 25, 42 and 50 lie 40 in the same plane and the axes of the shafts 42 and 50 are mutually inclined and make equal angles with the axis of the shaft 25. The gears 43 and 51 mesh with the gear 26.

The flanges 56 and 57 are secured respectively to the flanges 49 and 55 by means 45 of bolts such as 58.

The flanges 56 and 57 are preferably of metal and are secured in any approved manner respectively to the lower ends of the insulators 59 and 60. The flanges 61 and 62 are secured in any approved manner respectively to the upper ends of the insulators 59 and 60.

To each of the flanges 61 and 62 there is 55 secured a switch bracket 63 by means of bolts such as 64. The switch bracket 63 consists of the flange 65 formed integrally with the cylindrical boss 66; a plurality of strengthening ribs such as 67 is formed integrally with said flange and boss. The boss 66 is provided with a central cylindrical hole in which fits tightly the cylindrical stud 68, said stud being further secured in 60 said boss by means of the pin 69 which fits 65 tightly in holes provided in both. A T

head 70 is formed integrally with the upper end of the stud 68 and said head is provided with a hole at right angles to the axis of said stud in which hole is fitted tightly one end of the switch arm 71, the latter being secured in place in said head by means of the pin 72 which fits tightly in holes provided in both, (see Fig. 9.)

A boss 73 and ribs 74 are formed integrally with the T head 70. The lower end 75 of the discharge horn 75 fits tightly in a cylindrical hole provided in the boss 73 and is retained in place therein by the pin 76 which fits tightly in holes provided in both.

The interior surface of the sleet hood 77 fits on the exterior surfaces of the ribs 74 and said hood is secured in place by means of a screw 78.

The connector 79 is provided with a cylindrical hole in which the stud 68 fits loosely. The connector 79 fits loosely between the opposing faces of the boss 66 and the T head 70. The connector 79 is provided with a boss 80 having cylindrical holes 81 and 82 formed therein; in the former there is placed one end of the flexible connection 83 and in the latter the line connection 84; said connections being secured in place by screws such as 85.

The other end of the line connection 84 is secured in one branch of the Y connector 86 to the stem of which the line 87 is secured. To the other branch of the Y there is secured in any approved manner one end 100 of the strain insulator 88, the other end of which is secured to the screw eye 89 mounted in the angle 16.

The arm 71 is preferably formed of a tube, and shaped as shown in plan view in 105 Fig. 2. At the inner end of the arm 71 the walls of said tube are swaged together to form the flat portion 90 and said flat portion thus formed is bent inwardly as at 91 and terminates in the flat portion 92, which 110 is substantially parallel to a plane passing through the axes of the shafts 42 and 50.

The contact spring 93 is secured to the flat portion 90 by a screw 94 and said spring extends through a slot 95 formed in the flat portion 92, said spring being bent into the form of a U as at 96 and the end of said spring enters a slot provided in the contact block 97. Between the U 96 and the screw 94 the contact block 98 is secured to the 120 spring 93 by means of a screw 99. A washer 100 and a thin leaf of copper 101 is secured between the head of the screw 99 and the spring 93. Said thin copper leaf follows the contour of the spring 93 and the end 125 thereof enters the slot in the contact block 97. The block 97, the end of the spring 93 and the ends of the leaf 101 are provided with holes through which is passed a rivet 102 whereby said spring and leaf are secured 130

in good mechanical and electrical connection to the block 97. In order to provide greater flexibility the copper leaves are provided with a U shaped loop as at 103. The block 97 is flexibly secured to the flat portion 92 by the screw 104 which passes loosely through a hole provided in said portion and is threaded in a hole provided in said block.

The connecting stud 105 is formed integrally with the block 98 and said stud extends loosely through the hole 106 provided in the flat portion 90 and the movement of the block 98 away from the flat portion 90 is limited by the nut 107 which is threaded upon the stud 105. The stud 105 is provided with a hole 108 in which is placed one end of the flexible connection 83, the latter being secured in place by means of the screw 109. An adjusting rod 110 has one end secured to the arm 71 and upon the other end is threaded one end of the turn buckle 111, the other end of said turn buckle being threaded upon one end of the adjusting rod 112, the other end of which is threaded into the boss 113 formed integrally with the flange 65.

The other contact arm 114 is provided at its inner end with a contact constructed the same as the contact just described. This contact includes the contact block 115 which is similar to the contact block 97 and the contact block 116 which is similar to the contact block 98. The contact block 116 is provided with the stud 117, the latter being connected through the flexible connection 118 and the line connection 119 to a line similar to 87, the end of said line being supported by the strain insulator 120. Adjusting rods 121 and 122 and a turn buckle 123 are provided for adjusting the inner end of the arm 114 in the same manner as will be hereafter explained with reference to the adjustment of the inner end of the arm 71.

Curved sleet hoods 124—124 are secured at one end to the free end of the arm 114 and curved sleet hoods 125—125 are secured at one end to the free end of the arm 71, the opposing free ends of said hoods being sufficiently far apart to provide for the passage of the arms 71 and 114 between said ends when said contacts are separated. Each pair of said hoods partially surrounds the contacts as shown in Fig. 6.

The hood 126 is provided around the gear housing 19 and is secured thereto in any approved manner as by screws 127.

It is evident that any desired number of my improved switches may be mounted in juxtaposition upon the angles 16—16 and that each of said switches may be operated by a separate operating rod such as 37; it is also evident that a plurality of said switches may be simultaneously operated by one operating rod such as 37 by connecting said rod to the lever 32 of each switch.

The operation of my improved high potential switch is as follows:

The parts being in the position shown in the figures, if now the rod 37 is moved in the direction of the arrow 128 in Fig. 2 it will 70 turn the gear 26 in the direction of the arrow 129 in Fig. 1. This will turn the gear 51 and insulator 60 in the direction of the arrow 130 and the gear 43 and insulator 59 in the direction of the arrow 131 (see 75 Fig. 1.) This will move the arms 71 and 114 in the direction of the arrows in Fig. 7 and will separate the contact blocks 97 and 98 from the contact blocks 115 and 116 and arcs will form between the end of the contact block 97 and the arm 114 and between the end of the contact block 115 and the arm 71. The continued motion of the arms 71 and 114 in the direction of the arrows in Fig. 7 will bring said arms in such position 85 that the arc will extend between same and as said arms are moved around, the arc will be gradually increased in length until it will finally be transferred to the discharge horns 75 and 132, whence passing upwardly, owing 90 to the inclined position of said horns, the arc will be stretched and finally extinguished.

It is to be noted that by the use of the curved arms 71 and 114, which are approximately semicircular in shape, a magnetic field is induced by the current flowing therethrough, which field develops a normal tendency in the arc to remain in the plane passing through the discharge horns. 95

When the circuit is to be closed the rod 37 is moved in the direction opposite to that just described and the arms 71 and 114 are moved in the direction opposite to the direction of the arrows in Fig. 7, thus bringing the parts into the relative positions shown in the drawings and closing the circuit. The line current will flow from the line 87 through the line connector 84 to the connector 79, thence through the flexible connection 83 and arm 71 to the contact blocks 97 and 98, thence through the contact blocks 115 and 116 to the arm 114 and the flexible connection 118, thence to the line connector 119. 105

It is to be noted that by adjusting the turn buckles 111 and 123 the loci of the contacts supported by the inner ends of the arms 71 and 114 respectively may be varied so that the contact blocks 97 and 98 may contact 110 with the contact blocks 115 and 116 with any desired degree of pressure.

I claim:

1. In an electric switch, the combination with a pair of arms, of a contact mounted 125 on one end of each arm, and located to mutually contact an axially revoluble insulator supporting the other end of each arm and means for rotating said arms.
2. In an electric switch, the combination 130

- with a pair of arms, of a contact mounted on one end of each arm, an axially revoluble insulator supporting the other end of each arm and means for rotating said arms in opposite directions.
3. In an electric switch, the combination with a pair of arms, of a contact mounted on one end of each arm, revoluble supports for the other ends of said arms having axes 10 mutually inclined, discharge horns axially in line with said supports, gears on said supports and a gear for turning said gears.
4. In an electric switch, the combination with a pair of arms, of a contact mounted on 15 one end of each arm, axially revoluble insulating supports for the other ends of said arms, and means for turning said supports, said arms comprising curved portions forming part of the electric circuit and arcing 20 surface.
5. In an electric switch, the combination with a pair of arms, of a contact mounted on one end of each arm, revoluble supports for the other ends of said arms having 25 their axes located in the same plane, a discharge horn mounted on each support in axial alinement therewith, a circuit including said arms and carrying a current of electricity and means for turning said supports to open said circuit; said arms comprising curved portions for conducting said current in a path located to induce a magnetic flux for giving the arc formed when 30 said circuit is opened a normal tendency toward the plane including the axes of said horns.
6. In an electric switch, the combination with a base, of a pair of mutually inclined shafts revolubly mounted in said base, means 40 for revolving said shafts, an insulator supported by each shaft, an arm supported by each insulator, a contact upon the end of each arm, a discharge horn mounted upon each arm in axial alinement with the corresponding shaft and a line connection to the end of each arm.
7. In an electric switch, the combination with a pair of curved arms, of a contact mounted on one end of each arm, a revoluble support for the other end of each arm, 50 means for rotating said arms and means for varying the distance of each contact from the axis of the support of the corresponding arm.
8. In an electric switch, the combination 55 with a base, of a pair of mutually inclined shafts revolubly mounted in said base, means for revolving said shafts, an insulator supported by each shaft, an arm supported by each insulator, a contact upon the end of each arm, a discharge horn mounted upon each arm in axial alinement with the corresponding shaft, a connector swiveled to each arm and a flexible connection between each connector and contact. 65
9. In an electric switch, a pair of switch arms, means for revolubly supporting one end of each arm, and a contact mounted upon the other end of each arm, each contact comprising a parallel block and a 70 wedge-shaped block and a spring connection between said blocks and between said blocks and said arm.
10. In an electric switch, the combination with a pair of curved arms, of a contact 75 mounted on one end of each, a revoluble support for the other end of each arm, means for rotating said arms and a connection between each support and each arm near said contact whereby the distance of 80 each contact from the axis of the support of the corresponding arm may be varied.
11. In an electric switch, the combination with a pair of arms, of a contact mounted upon one end of each arm, a revoluble support for the other end of each arm, means 85 for rotating said arms and a sleeve hood mounted upon each arm and partially encircling said contact.

In testimony whereof, I affix my signature. 90

GEO. T. SOUTHGATE.
